TRIPOD HEAD

Elias Edward Resk, 645 Pine Brook Blvd.,
New Rochelle, N.Y. 10804

Filed Aug. 21, 1968, Ser. No. 13,231

Term of patent 14 years

Int. Cl. D16—07

U.S. Cl. D61—1

FIG. 1 is a perspective view of a tripod head showing my new design;

FIG. 2 is a side elevational view;

FIG. 3 is an end elevational view; and

FIG. 4 is a bottom view.

The dominant features of my new design reside in those portions shown in full lines, the adjustment handles and knobs shown in broken lines are for illustrative purposes only.

I claim:

The ornamental design for a tripod head, substantially as shown and described.
